UNITED STATES PATENT OFFICE

91,640

DESIGN FOR A COMBINED PICTURE FRAME AND CONVEX GLASS

Herman A. Tidemann, Toronto, Ontario, Canada

Application August 10, 1933, Serial No. 48,981

Term of patent 3½ years

To all whom it may concern:

Be it known that I, HERMAN A. TIDEMANN, a British subject, residing at the city of Toronto, in the county of York and Province of Ontario, Dominion of Canada, have invented a new, original, and ornamental Design for a Combined Picture Frame and Convex Glass, of which the following is a specification, reference being had to the accompanying drawing forming part thereof.

Figure 1 is a front view; and

Figure 2 is a side view.

The said ornamental design of picture frame

and convex glass consists of the bottom portion of the combination being horizontal curving upwards at the sides to rounded scallops located at approximately three quarters of the height of the combination then curving arcuately to the top where it is capped by the arc of a circle.

I claim:

The ornamental design for a combined picture frame and convex glass substantially as shown and described.

HERMAN A. TIDEMANN.
